UNITED STATES PATENT OFFICE

CHARLES HATAY, OF BERLIN-CHARLOTTENBURG, GERMANY, ASSIGNOR TO GENERAL ELECTRIC COMPANY, A CORPORATION OF NEW YORK

SWITCHING DEVICE

Application filed May 1, 1929, Serial No. 359,651, and in Germany May 7, 1928.

My invention refers to switching devices and more especially to a mercury switch. It is an object of my invention to provide means whereby the life of such switches is prolonged.

In the mercury switch tubes of the prior art the arc formed during the switching operation gradually causes erosion of the glass walls so that finally cracks and fissures will 10 form in the glass which may lead to destruction of the tube. Even before these conditions have arisen small glass particles split off the walls and float on the surface of the mercury, giving rise to undesirable disturbances.

It has already been suggested that these drawbacks might be obviated by replacing the glass tubes by quartz tubes, but the high price of the latter rendered this suggestion 20 impractical for commercial purposes.

According to the present invention the drawbacks aforementioned are obviated by providing the glass tube with a lining of highly resistive material. The term "highly resistive material" as used in this specification and the claims appended to it is intended 25 to include particularly resistive kinds of glass as well as quartz and other similar materials. This lining need not cover the entire 30 inner surface of the tube but may extend only over part of the surface. Preferably instead of a lining firmly adhering to the glass tube, a vessel may be loosely inserted in the tube. As compared with a tubular insert open at both ends a vessel closed at one 35 end offers the advantage of preventing the passage of mercury between the wall of the tube and the vessel and the entrance of mercury into the vessel from the rear side. In 40 addition a vessel closed at one end can easily be fixed in its correct position by means of the electrodes without any particular fixing means being required.

In the drawing affixed to the specification 45 and forming part thereof, several devices embodying my invention are illustrated diagrammatically by way of example.

In the drawing:

Fig. 1 is a mercury switch tube with a 50 quartz or other vessel inserted therein, this

vessel being formed substantially similar to the part of the tube in which it is arranged.

Figs. 2 and 3 are axial sections illustrating two other forms of vessels, and

Fig. 4 is an elevation of another mercury 55 switch tube with a fourth form of a vessel inserted therein.

Referring first to Fig. 1, 1 is the glass tube closed at one end by a round bottom and 2 is a vessel consisting of quartz or of a particularly resistive kind of glass and having a bottom rounded to fit into the bottom portion of the glass tube, the other end of the vessel being open. 3 and 4 are the two electrodes, which are bent in such fashion that 60 they keep the vessel fixed in the bottom portion of the tube.

It is obvious, however, that if the switch tube shown in Fig. 1 is tilted through an unduly great angle, all the mercury will escape 65 from the vessel 2, resulting in an arc between the mercury and the electrode 4. A vessel such as illustrated in Fig. 2, which will prevent the escape of all the mercury, is therefore preferred. This vessel is formed with a 70 constricted portion 5 extending circumferentially around the vessel between the electrodes 3 and 4, so that even if this vessel is tilted through a considerable angle, some 75 mercury will nevertheless be left in the bottom portion of the vessel.

In the modification illustrated in Fig. 3 the constriction 5 shown in Fig. 2 is replaced by a mere indenture 6 serving the same purpose. Obviously this form of a vessel can 80 be manufactured at a lower price, but means must here be provided for preventing angular displacement of the vessel in the tube.

In the switch illustrated in Fig. 4 the 85 danger that the inner electrode 4 might be left without any mercury is prevented, since the vessel 7 is formed with an inwardly directed tubular flange or reentrant portion 8 which always retains an appreciable amount of mercury. The electrode 9 extends 90 into the vessel and is bent, so that its end extends into the pool of mercury retained between the outer wall of the vessel 7 and the reentrant portion 8. Obviously with this 95 form of the lining vessel the free end of the 100

electrode 9 will always be immersed in mercury.

I wish it to be understood that I do not desire to be limited to the exact details of construction shown and described for obvious modifications will occur to a person skilled in the art.

I claim:—

- 10 1. A mercury switch comprising a sealed tube containing mercury, electrodes sealed into said tube, and a lining of highly resistive material within said tube, said lining having a pocket therein which cooperates with the remainder of said lining to retain a
- 15 18 pool of mercury in said lining at all positions of said switch, one of said electrodes terminating in said mercury pool at all operative positions of said switch.
- 20 2. A mercury switch comprising a sealed tube containing mercury, electrodes sealed therein, and a lining of highly resistive material within said tube, said lining being cup-shaped with a reentrant rim, whereby a pool of said mercury is retained within said
- 25 25 lining at all positions of said switch, one of said electrodes terminating in said pool of mercury.

In testimony whereof I affix my signature.
CHARLES HATAY.
